DEMOUNTABLE BLADE BIT

Alfred C. Catland, Alhambra, Calif., assignor to
 Globe Oil Tools Company, Los Nietos, Calif.,
 a corporation of California

Application August 11, 1937, Serial No. 158,515

6 Claims. (Cl. 255—61)

This invention relates to well drilling tools and relates more particularly to a well bit for use in the rotary method of well drilling. A general object of this invention is to provide a practical, effective, well bit embodying demountable and replaceable cutting blades.

It is highly desirable to make the blades of well drills demountable so that they may be replaced when worn or when it is desired to employ blades of different character. However, great difficulty has been encountered in providing a practical demountable blade well bit. In bits of this character heretofore introduced the blades hammered loose in the shank causing wearing of the shank and breaking of the blades.

Another object of this invention is to provide a well bit embodying demountable blades secured to the bit body in such a manner that they cannot work loose or hammer against the body.

Another object of this invention is to provide a demountable blade bit of the character mentioned in which the heavy cutting thrusts or forces are transmitted directly between the bit body and the blades and do not cause loosening of the blades or the securing means.

Another object of this invention is to provide a well bit of the character mentioned embodying novel means for locking the blades to the head or body of the tool.

Another object of this invention is to provide a bit of the character mentioned in which the cutting parts are formed, positioned and related to act on the entire bottom wall of the well bore and to be particularly rapid and efficient in their cutting action.

A further object of this invention is to provide a well bit of the character mentioned that is simple and inexpensive to manufacture and that may be easily and quickly reconditioned by replacing its cutting parts.

The various objects and features of my invention will be fully understood from the following detailed description of a typical, preferred form and application of the invention, throughout which description reference is made to the accompanying drawings, in which:

Fig. 1 is a front elevation of the improved bit provided by this invention. Fig. 2 is a side elevation of the bit. Fig. 3 is a bottom view of the bit. Fig. 4 is an enlarged fragmentary vertical detailed sectional view taken as indicated by line 4—4 on Fig. 3. Figs. 5 and 6 are transverse detailed sectional views taken as indicated by lines 5—5 and 6—6, respectively, on Fig. 4. Fig. 7 is a fragmentary vertical detailed sectional view

showing one of the choke nipples and adjacent parts. Fig. 8 is a rear elevation of one of the blades. Fig. 9 is a horizontal sectional view taken as indicated by line 9—9 on Fig. 8. Fig. 10 is a front elevation of one of the other blades. Fig. 11 is a horizontal sectional view taken as indicated by line 11—11 on Fig. 10 and Fig. 12 is an enlarged fragmentary vertical detailed sectional view taken as indicated by line 12—12 on Fig. 6.

The improved well bit provided by this invention includes, generally, a shank or body 10, a center cutter 11 on the lower end of the body 10, pairs of demountable blades 12 and 13 and means 14 removably securing the pairs of blades 12 and 13 to the body 10.

The body 10 is adapted to be connected with the lower end of a rotary well drilling string. In practice the body 10 is an elongate member provided at its upper end with a threaded pin 15 for facilitating its connection with the drilling string. The lower portion of the body 10 may be enlarged in diameter to carry the cutting parts. The enlarged lower portion of the body 10 may have two diametrically opposite flat side faces 16. Pockets or recesses 17 are provided in diametrically opposite sides of the large lower portion of the body 10. The recesses 17 are of substantial length and extend upwardly from the lower end of the body. The two recesses 17 are offset rearwardly relative to the direction of rotation of the bit with respect to a diametric plane parallel with the side faces 16. The upper walls 18 of the recesses 17 are flat and substantially horizontal. The bottom walls or inner walls of the recesses 17 are flat and substantially vertical. In accordance with the invention the recesses 17 have flat inwardly convergent side walls 19. The side walls 19 are inclined downwardly and forwardly relative to the direction of rotation of the bit. Vertically or longitudinally extending grooves 20 are provided in the corners of the recesses 17 where their side walls 19 join their inner walls. The grooves 20 are preferably partially cylindrical in cross section to facilitate the manufacture of the body 10. A horizontal flat walled groove 21 is provided in the inner wall of each recess 17. The grooves 21 extend between and communicate with the spaced grooves 20.

The center cutter 11 is provided to cut away the earth formation at the center of the well bore. The center cutter 11 projects from the lower end of the body 10 and is demountable and replaceable. The removable center cutter 11 includes a body or pin 22 which is threaded 23

in a central socket 23 in the lower end of the body 10. The cutter 11 further includes fish-tail blades 24 on the lower end of the pin 22. The blades 24 project downwardly beyond the lower end of the body 10. The blades 24 are preferably of substantial width to act on or remove the earth formation remaining within the path of the blades 12 and 13. The center cutter 11 may be readily removed from the body 10 by unthreading its pin 22 from the socket 23.

The blades 12 and 13 are the principal cutting elements of the bit. There are two pairs of blades 12 and 13, one pair being secured in each recess 17. The blades 12 are arranged in the forward portions of the recesses 17 relative to the direction of rotation of the bit while the blades 13 are arranged in the rear portions of the recesses. The blades 12 and 13 may be substantially identical although they embody lock parts of the means 14 that are slightly different in position. The blades 12 and 13 are plate-like elements having flat parallel opposite sides. Shanks 25 and 25^a of reduced width are provided on the upper ends of the blades 12 and 13, respectively. Suitably bevelled reaming edges 26 and 26^a are provided on the blades 12 and 13. The reaming edges 26 and 26^a are of substantial length and when the blades are in position on the body 10 the edges 26 and 26^a extend from above the lower end of the shank to points some distance below the lower end of the shank. The lower ends of the blades 12 and 13 are shaped to have effective cutting engagement with the earth formation. In the particular case illustrated in the drawings the lower ends of the blades 12 and 13 are alike, the blades 12 each having two stepped cutting edges 27 and 28 and the blades 13 each having two similar cutting edges 27^a and 28^a. It is to be understood that the lower ends of the trailing blades 13 may be different from the lower ends of the leading blades 12, for example, their lower ends may be straight and without the notch or step shown.

The means 14 for securing the blades 12 and 13 to the body 10 is an important feature of the invention and is such that the blades may be easily and quickly removed from the body 10 for replacement, etc. The means 14 includes ribs or tongues 30 and 30^a, respectively, on the inner vertical edges of the blades 12 and 13. The tongues 30 and 30^a are provided to cooperate with the grooves 20, and are partially cylindrical in cross section to accurately fit the grooves. The tongues 30 and 30^a are preferably formed integral with the blades 12 and 13. Notches 31 are provided in the inner edges of the blades 12 and extend through their tongues 30 and similar notches 32 are provided in the inner edges of the blades 13 and extend through their tongues 30^a. When the blades 12 are in cutting position on the shank 10 their forward sides bear on the forward walls 19 of the recesses 17 and their upper ends bear directly on the upper walls 18 of the recesses. In a like manner when the blades 13 are in place their rear sides bear on the pitched rear side walls 19 of the recesses 17 and their upper ends bear directly against the upper walls 18 of the recesses 17. The tongues 30 and 30^a cooperate with the grooves 20 to lock the blades 12 and 13 against outward or radial displacement and movement relative to the body 10. It will be observed that the blades 12 and 13 bearing against the inclined side walls 19 of the recesses 17 slope downwardly and forwardly with respect to the direction of rotation of the bit.

The means 14 further includes a wedge or block 33 arranged in each recess 17 to retain the blades 12 and 13 in place. The blocks 33 are shaped and proportioned to properly cooperate with the blades 12 and 13 and to definitely prevent movement and hammering of the blades. The blocks 33 have flat upper ends 34 bearing against the upper walls 18 of the recesses 17. The outer sides of the blocks 33 may be convex and substantially flush with the adjacent surfaces of the body 10. The inner sides 35 of the blocks 33 are flat and vertical. A horizontal lug 36 is provided on the inner side 35 of each block 33. The lugs 36 fit the grooves 21 in the body 10 and cooperate with the notches 31 and 32 in the blades 12 and 13, respectively. The lugs 36 cooperating with the notches 31 and 32 definitely locate the blades 12 and 13 on the body 10 and assist in preventing downward displacement of the blades. The ends of the lugs 36 are flat and cooperate with the flat bottom or inner walls of the notches 31 and 32.

The sides 37 of the blocks 33 are inwardly convergent and are inclined downwardly and forwardly relative to the direction of rotation of the bit to flatly bear on the rear surfaces of the blades 12 and the front surfaces of the blades 13. The blocks 33 are proportioned so that their inner sides 35 have suitable clearance with the inner walls of the recesses 17 when their sides 37 are in cooperation with the blades 12 and 13. The inner corners of the blocks 33 may be shaped to receive portions of the tongues 30 and 30^a that protrude from their grooves 20.

The means 14 includes securing members for attaching the blocks 33 to the body 10 and to urge the blocks inwardly against the blades 12 and 13 so that the blocks securely hold the blades on the body. In the preferred construction two vertically spaced studs 38 project outwardly from the inner wall of each recess 17. The studs 38 may be threaded in openings 39 in the body 10 and then welded to the body. Horizontal openings 40 are provided in the blocks 33 and receive the projecting portions of the studs 38. Nuts 41 are threaded on the studs 38 and bear inwardly against the blocks 33. The nuts 41 are preferably received in the outer portions of the openings 40. Cotter keys 42 may lock the nuts 41 against unthreading. The nuts 41 bearing inwardly against the tapered wedge-like blocks 33 urge the blocks against the blades 12 and 13 so that they securely hold the blades in place against the inclined and inwardly convergent walls 19. The tapered blocks 33 also urge the blades 12 and 13 inwardly to hold their tongues 30 and 30^a tight in the grooves 20.

The invention provides effective means for flushing the cutter 11 and the blades 12 and for maintaining a proper circulation in the well. A central longitudinal fluid passage 43 extends downwardly in the body 10 from the upper end of its pin 15 and receives the circulation fluid from the drilling string. The lower portion of the passage 43 is reduced in diameter. Ports 44 of reduced diameter communicate with the reduced lower part of the passage 43 and extend downwardly and outwardly to the lower end of the body 10. Choke nipples 45 are provided at the lower ends of the ports 44 to increase the velocity of the discharged fluid and to prevent the fluid from wearing away the body 10. The nipples 45 discharge immediately in front of the leading blades 12 and are effective in preventing mud and cuttings from accumulating on the

blades. A central port 46 of reduced diameter extends downwardly from the reduced lower end of the passage 43 to the socket 23 where it communicates with a passage 47 in the pin 22. Two downwardly and outwardly inclined ports 48 communicate with the lower end of the passage 47 and discharge from the lower end of the cutter 11 in front of its blades 24.

It is believed that the operation of the bit 10 provided by this invention will be readily understood from the foregoing detailed description. In operation the body 10 is connected with the lower end of a well drilling string and the bit is rotated and fed downwardly in the well in the usual manner. The leading blades 12 are effective in cutting away the formation at the bottom of the well bore and the trailing blades 13 assist in cutting away the formation and operate to stabilize the bit. The pairs of blades 12 and 13 make an annular cut in the earth formation leaving a central portion. This central portion of the earth formation is cut away by the center cutter 11. The reaming edges 26 and 26^a of the blades 12 and 13, respectively, ream the side wall of the well bore and assist in stabilizing and guiding the bit to drill a straight bore. The circulation fluid discharged from the nipples 45 and from the ports 48 flushes the blades and the cutter 11 and maintains a desirable turbulence in the bottom of the well.

The wedge blocks 33 forced or urged inwardly by the nuts 41 hold the blades 12 and 13 in tight contact with the surfaces of the body 10 so that the blades cannot hammer against the body. The wedge-like blocks 33 bearing inwardly against the blades 12 and 13 urge the blades radially inward as well as laterally against the side walls 19 of the recesses 17 dependably preventing hammering and working of the blades. The upper ends of the blade shanks 25 and 25^a bear directly against the upper walls 18 of the recesses 17 for the transmission of the heavy drilling pressures. This relieves the studs 38 and the lugs 36 of these heavy forces, although the studs and the lugs may assist in the transmission of some of the cutting forces. As the inner sides 35 of the blocks 33 have clearance with the inner walls of the recesses 17 the blocks may be forced into very tight holding engagement with the blades 12 and 13 by tightening down the nuts 41. When it is desired to replace the blades 12 and 13 it is only necessary to unthread the nuts 41 and then remove the blocks 33 to free the blades for removal. New blades or replacement blades 12 and 13 may be quickly assembled on the body 10 to recondition the bit or to change the effective cutting diameter of the bit.

Having described only a typical preferred form and application of my invention I do not wish to be limited or restricted to the specific details herein set forth, but wish to reserve to myself any variations or modifications that may appear to those skilled in the art or fall within the scope of the following claims.

Having described my invention, I claim:

1. A well bit comprising a body having a recess with inwardly converging side walls, there being

grooves in the body at the inner edges of said side walls, cutting blades engaged against said side walls, tongues on the blades cooperating with said grooves, and a removable block in the recess having inwardly converging sides bearing on the blades to retain the blades in position, the grooves having open sides facing outwardly whereby the blades may be moved laterally to disengage their tongues from the grooves when the block is removed.

2. A well bit comprising a body having a recess with inwardly converging side walls, there being grooves in the side walls, cutting blades engaged against the opposite side walls of the recess, tongues on the blades cooperating with said grooves, a block in the recess having inwardly converging sides bearing against the blades, and screw means removably holding the block inwardly against the blades to retain the blades in position, the grooves having open sides facing outwardly whereby the blades may be moved laterally to disengage their tongues from the grooves when the block is removed.

3. A well bit comprising a body having a recess with inwardly converging side walls and an upper wall, there being grooves in the body at the inner parts of said side walls, cutting blades engaged against said side walls and bearing upwardly against said upper wall, tongues on the blades fitting said grooves, a block in the recess having inwardly converging sides engaging the blades, and means holding the block inwardly in the recess.

4. A well bit comprising a body having an external longitudinal recess provided with walls converging inwardly toward the vertical axis of the body, cutting blades arranged against the opposite convergent walls of the recess, the inner edges of the blades having notches, a block in the recess having inwardly convergent sides bearing on the blades to hold them against said convergent walls, a part on the block cooperating with said notches, and means holding the block in the recess.

5. A well bit comprising a body having a recess with side walls, there being grooves in the side walls, cutting blades arranged against the side walls, tongues on the blades cooperating with the grooves to prevent outward movement of the blades, a block in the recess engaging the blades, said tongues having notches, a part on the block cooperating with the notches to prevent vertical movement of the blades, and means urging the block against the blades.

6. A well bit comprising a body having recesses in its opposite sides, said recesses having side walls converging inwardly toward the vertical center of the body, a cutting blade arranged against each of said side walls and projecting downwardly from the body, a block in each recess, the blocks having inwardly convergent sides bearing on the blades, means removably holding the blocks in the recesses, cutting parts on the projecting low portions of the blades, and a center cutter removably secured to the body and projecting from its lower end.

ALFRED C. CATLAND.
